Filed Oct. 5, 1959, Ser. No. 844,417

Claims priority, application Great Britain Oct. 7, 1958
7 Claims. (Cl. 34—85)

This invention concerns the printing of fabrics and yarns (hereinafter called "material"), especially cellulosic fabrics, with vat and sulphur dyes.

Two-phase printing processes are known. In one such process cellulosic fabric is printed with vat dyestuff, dried, and padded with an alkaline reducing agent. Finally, steaming, oxidation, soaping off and like finishing operations are carried out in conventional manner. Improved selection of the reducing agent has resulted in reduced times for steaming being required.

Such two-stage processes as generally practised have certain disadvantages, one of the more serious being the incidence of marking-off. This usually occurs during the steaming process and is the more likely to occur with processes requiring only short steaming times because of the correspondingly greater concentration of reduced dyestuff at any given moment. In so-called "flash ageing," which is a two-stage process involving the use of a solution of caustic soda and sodium hydrosulphite, marking-off from the rollers during steaming is a major difficulty, and it is with this type of two-stage process that the present invention is more particularly concerned, its object being however, a general improvement in the process of fixing the dyestuff after it has been applied to a fabric or yarn in the initial stage of a two-stage process of the broad type which has been referred to hereinbefore.

According to the present invention a method of printing material, especially cellulosic fabrics with vat and sulphur dyes includes the stages of passing the material, printed with the dyestuff and treated with a reducing agent, around a system of heated rotating cylinders, the material being held against part of the periphery of each cylinder by a travelling band of fluid-tight material, and passing substantially directly from the peripheral surface of one cylinder to that of the next, whereby to reduce the dyestuff to the soluble form, and continuously cleaning the cylinder surfaces at another part of their peripheries.

The invention also includes a machine for the flash ageing of material, especially cellulosic fabrics which comprises a plurality of rotatable cylinders capable of being heated by internal means, an endless band of fluid-tight material, means for supporting said band around part of the periphery of each cylinder, so as to move with said cylinders when rotated and pass substantially directly and successively from the peripheral surface of one cylinder to that of the next, means for introducing said material between those parts of the cylinder surfaces and the band so that same is also progressed in like manner, and means for continuously cleaning the peripheral surfaces of the cylinders at another part of their peripheries when rotating.

The use of more than one cylinder, and the use of internally heated cylinders instead of a steam atmosphere is very practical because we have found, contrary to previous belief, that short passages in air (as is inevitable between cylinders) of the fabric are not detrimental, and because we have designed an efficient cleaning device for the rotating surface of a cylinder with a non-machined surface, normally built up from sheet metal, of the commercially available and inexpensive type. The prin-

2

ciples of the cleaning means will be illustrated in the following description of one particular process according to the invention, and apparatus for the carrying out thereof, reference being made to the accompanying drawings, in which:

FIGURES 1 and 1A are the two end elevations of a two-cylinder machine for the flash ageing of cellulosic fabrics;

FIGURE 2 is a front elevation as seen from the left of FIGURE 1, the fabric and travelling band being omitted;

FIGURE 3 is a scrap view showing in more detail the cylinder cleaning arrangements;

FIGURE 4 is a sectional end view of one of the cylinder cleaning devices; and

FIGURE 5 is a perspective view of one of the cylinder cleaning devices.

The drawings illustrate a two-cylinder machine for the flash ageing of cellulosic fabrics. The two cylinders 11, 12 are built up from sheet metal and approach four feet in diameter. They are disposed as illustrated, one vertically above the other with their axes horizontal. A system of parallel rollers, 13, 14, 15, 16, 17, 18, 19, 20, 21, 22, 23 support an endless band 24 of rubberised fabric or other suitable fluid-tight material for passage round the cylinders 11, 12, as shown, through a washing trough 25 divided into two sections each having a rotary brush 25a, one for applying cleaning liquid and the other for removing surplus liquid, and through a drying device 26 (if necessary). One roller 15 applies the tension to the band 24 whilst another roller 16 is adapted to act as a tracking roller to maintain the correct portion of the band axially of the cylinders. Padding mangle bowls 27, 28 are disposed so as to enable printed and padded fabric 29 to be fed into the machine between the band 24 and the cylinder 11. A reservoir 30 is provided for the liquor to be padded on and the bowl 28 dips into this. A further system of parallel rollers 31, 32, 33, 34, 35 are provided for guiding the fabric through the padding system and a grooved scroll bar 36 ensures the widthwise stressing of the fabric coming to the padding system. The fabric is progressed between the band 24 and the cylinders 11, 12 (the band being at least slightly wider than the fabric) the direction of rotation or progression of the various elements being as indicated by the arrows, finally to be led off at an elevated level.

Washing or cleaning means 37 is provided for each of the cylinders 11, 12 disposed between the points at which the fabric 29 enters and leaves contact therewith. The lower cleaning means 37 has along its trailing edge an absorbent squeegee 38, for example of felt which spreads condensed drops of moisture for rapid evaporation from the surface of the cylinder 11. It is not necessary to make such provision in the upper cylinder 12 since the location of the upper cylinder washer is such that condensate falling therefrom will fall onto the lower cylinder washer.

In practice, the roller 22 is closer to the line joining the centres of cylinders 11 and 12 than is shown in the drawings, thus the fabric moving round the roller is less likely to be contaminated by drops of moisture falling from the upper cleaning means.

Referring more particularly to FIGURE 1, an electric motor or other prime mover (not shown) drives a chain wheel assembly 39 and by means of chains 40, 41, the drive is transmitted respectively to a chain wheel 42 associated with the lower cylinder 11 to rotate the latter, and to a chain wheel 43 associated with the roller 21, to rotate the latter and, through a further chain 44, chain wheel 45 associated with roller 22, and chain wheel 46 associated with roller 23 to rotate rollers 22, 23. It is

desirable that the drive to the rollers 21, 22, 23 should be through a slipping clutch (not shown) so that, in the event of slip occurring between the band 24 and the rollers 11 and 12 the rollers 21, 22, 23 can take over the driving of band 24. This arrangement also compensates for cylinder non-uniformity. A further prime mover (not shown) drives a chain wheel 47 and by means of a chain 48 the drive is transmitted to a chain wheel 49 associated with the lower mangle bowl 28 whereby to rotate the latter.

Referring more particularly to FIGURE 1A both cylinders 11, 12 are provided at the other side with chain wheels 50, 51 and chain 52 transmits the drive from the lower cylinder 11 to the upper cylinder 12.

The roller 35 (FIGURE 1) is preferably arranged to be sensitive to the fabric tension, and to cause the speed of the cylinders 11, 12 relative to that of the mangle bowl 28 to be adjusted by a variable gear so that substantially constant fabric tension is achieved. The top mangle bowl 27 has (FIGURE 2) an assembly 55 associated with each of its bearings whereby the mangling pressure can be adjusted.

Steam inlet pipes 53 and outlet pipes 54 are provided whereby the steam necessary to heat the cylinders 11, 12 is introduced thereto and removed therefrom.

Referring now to FIGURES 3, 4 and 5 the cleaning means or washer 37 for the surfaces of cylinders 11, 12 will now be described in more detail.

Each washing or cleaning means 37 consists of a box-like structure with its only open side towards the cylinder periphery, suitable sealing means between this and the cylinder surface, a brush element, and means for passing cleaning water therethrough. The sealing means is a polytetrafluoro-ethylene gasket 55, .010 inch thick bonded to a three-eighths of an inch thick microcellular (non-connecting cells) synthetic rubber layer 56, which is in turn firmly fixed to the main box 57 of the washer, which is of metal, and in turn itself supported by a channel iron 57a. In the main box 57 is disposed a brush 58 supported at intervals along its length by pieces of microcellular synthetic rubber, and which extends across the operative width of the respective cylinder, the bristles 58a of which contact the cylinder. Water inlet and outlet pipes 59, 60 are provided at the base of the washer to enable water to pass to and from the brush region. To avoid undue distortion of the micro-cellular synthetic rubber we have found that the washer should have three-quarter inch walls, and the gasket and synthetic rubber layer should be of a like extent. In practice, we make the wall thickness of the main box 57 slightly greater than the lateral extent of the layer 56. The lateral extent of the gasket 55 where it overlies the layer 56 is in excess of that of the layer 56 to prevent wear of the latter where it tends to be pressed out laterally during operation of the cleaning device.

Each washer 37 is urged into contact with the respective cylinder wall by spring or screw means, the force exerted by which is adequate to ensure a sealing effect, but not sufficient to cause any undue braking effect on the cylinders 11, 12. We prefer to support each cleaning means or washer 37 in a rigidly mounted channel 61 running across the width of the machine and to load the device into sealing contact with its cylinder by means of compression springs housed in mountings 62 which have screw caps whereby the spring force exerted can be varied. We have found four such springs equi-spaced across the width of the machine to be an adequate number.

In operation we have found that for completely effective removal of printing paste from the cylinder, it is necessary to pass water continually through the washer, or cleaning means, via the inlet and outlet pipes. Suction may be applied to the outlet side as a precaution

against water being forced past the seal. The cleaning arrangement just described has been found to operate satisfactorily on the un-machined cylinders.

In a modified arrangement a gulley, and a drain means therefor, is provided in the face of the cleaning means which contacts the cylinder surface, as a safeguard in case any small leaks should occur.

When using the apparatus described, we heat the cylinders by suitable internal means, such as steam, to the appropriate temperature for reduction and continuously pass the fabric (or a plurality of ends of yarn) printed and padded between the band 24 and the cylinders 11, 12. The printed side of the fabric may be against the cylinders. The band 24 and the cylinder surfaces are continuously cleaned and we have found that good results were obtained, with marking-off eliminated. When using suitable reducing agents, the reduction time is very short. The passage in air when the fabric moves between the cylinders has no deleterious effect.

Advantages which result from the use of a plurality of cylinders is that output speeds may be increased, and space saved.

The invention is not limited to the details of the embodiment just described and improvements and modifications may be made. Thus, more than two cylinders can be used; the temperature of the respective cylinders may be arranged to be different, as may be best suit the circumstances, this being a further advantage of using more than one cylinder; and so forth.

We claim:

1. In a machine for the flash ageing of material especially cellulosic fabrics, which machine comprises a plurality of rotatable cylinders capable of being heated by internal means, an endless band of fluid-tight material, means for supporting said band around part of the periphery of each cylinder, so as to move with said cylinders when rotated and pass substantially directly and successively from the peripheral surface of one cylinder to that of the next, and means for introducing said material between those parts of the surfaces and the band so that same is also progressed in like manner, the improvement which comprises a box-like cylinder cleaning member for the surfaces of the respective cylinders with only one open side, said open side being in opposed relation to the surface of its respective cylinder, a brush therewith the bristles of which extend to said open side, a liquid inlet and outlet means in connection with the interior of said member, the box-like member being loaded against the cylinder surface with the interposition of sealing means, whereby to cause the brush bristles to contact the cylinder surface and to enable cleaning liquid to be continuously circulated therethrough, both while the cylinder is rotating.

2. A machine according to claim 1 in which the sealing means comprises a thin gasket of polytetrafluoro-ethylene lying against the cylinder surface supported on a resilient layer.

3. A machine according to claim 2 in which the gasket is approximately .010 inch thick.

4. A machine according to claim 1 including a resilient layer is approximately three-eighths of an inch thick, rubber between said sealing means and the main body of said cleaning means.

5. A machine according to claim 4 in which resilient layer is approximately three-eighths of a inch thick.

6. A machine according to claim 1 in which the lateral extent of the walls of the gasket, the resilient layer and box-like member is at least three-quarters of an inch.

7. A machine according to claim 1 in which a squeegee of absorbent material is adapted to contact the cylinder surface adjacent the trailing edge of the box-like member.
